CONNECTER SWITCH

Filed April 18, 1928

UNITED STATES PATENT OFFICE

NORMAN H. SAUNDERS, OF HOMEWOOD, ILLINOIS, ASSIGNOR TO RESERVE HOLDING COMPANY, OF KANSAS CITY, MISSOURI, A CORPORATION OF DELAWARE

CONNECTER SWITCH

Application filed April 18, 1928. Serial No. 270,879.

The present invention relates in general to automatic telephone systems and the principal object, stated briefly, is the provision of an improved connecter switch for use in a small automatic exchange for connecting with local subscribers' lines or with trunk lines extending to a toll recording operator's position or to adjacent branch exchanges.

The improved connecter switches are designed primarily for use in small automatic exchanges in which the capacity does not exceed a hundred lines, and, in addition to having access to local subscribers' lines, have access to groups of trunk lines, one group of which extends to a toll recording operator's position while the other groups extend to adjacent branch exchanges. In order to complete connections to the trunk lines, the connecters are directly operated into engagement with the first trunk line in the group from where, if such trunk line is busy, the connecters automatically hunt for an idle trunk line in the group, and in case all the trunk lines of the group are busy, come to rest on the contacts of the last trunk line of the group and transmit the busy tone to the calling subscriber.

One of the features of the invention relates to the improved impulsing and stepping control circuits of the connecter for directly and automatically controlling the operation of the connecter switch.

Another feature relates to the method of maintaining the automatic stepping circuit and for quickly switching through on trunk hunting levels by rendering a relay slow to release by short-circuiting the same as long as the switch wipers engage busy trunk lines, and by removing the short circuit when an idle trunk line is encountered to allow said relay to fall back quickly and establish the switching through circuit.

Another feature relates to the provision of two switching relays for a switch having only a single set of switch wipers and in which each switching relay is operated, when an idle line is encountered, independent of the other, depending, however, upon whether the switch has been operated to a trunk hunting

level or to a level in which local subscribers' lines terminate.

A further feature relates to the provision of a single condenser of relatively small capacity which is included in the circuit for transmitting a dial tone, a busy tone, or a ring-back tone to the calling subscriber.

In a system of this size, it often happens that it is desirable to meter all completed local connections and also to restrict certain subscribers to local connections, while other subscribers are allowed unrestricted service; that is, the unrestricted subscribers are entitled to originate toll calls and calls to the adjacent branch exchanges, while the restricted subscribers are unable, from their lines, to extend a connection to a toll operator or to a trunk line extending to an adjacent branch exchange. In this manner, the operators know that all calls extended thus far are entitled to have their desired connections completed. Another feature, in connection with the above, relates to the novel circuit arrangements by means of which metering and restricted service is controlled over the same conductor.

In order to provide supervision to the operator in a hundred-line system employing plunger type lineswitches, separate connecter switches, which reverse battery when the called party answers, were heretofore provided solely for the use of operators in completing connections to local subscribers, while the regular connecters accessible to the local subscribers' lineswitches did not reverse battery when the called party answered. It was impracticable, heretofore, to have connecter switches which reversed battery accessible to both subscribers and operators because on local connections, when the calling subscriber hung up his receiver before the called subscriber, there was danger of the bridge cut-off armature of the lineswitch fluttering or releasing and re-operating intermittently until the called subscriber hung up. This fluttering would occur in the following manner: When the calling subscriber replaces his receiver, the line and release relays of the connecter deenergize, and the release relay, upon removing holding ground from the release

trunk, causes the release of the bridge cut-off armature of the lineswitch before the plunger arm is effectively withdrawn from the switch banks. As soon as the bridge cut-off springs close, a circuit is established from ground through the lower winding of the line relay of the connector, through the upper reversing springs of the back bridge relay which is held energized by the called party, 10 through the lineswitch bank contacts, and through the bridge cut-off armature springs of the lineswitch to the line relay and battery at the lineswitch. This results in the re-energization of the line relays of both the lineswitch and connector, the re-energization of the release relay of the connector before the connector has had time to release, and the re-energization of the pull down winding of the lineswitch. The release relay of the connector again connects ground to the release trunk, thereby re-establishing the holding circuits for the ring cut-off and switching relays of the connector before they could return to their normal positions and for the bridge 20 cut-off windings. Since the bridge cut-off winding of the lineswitch is again energized, the circuit of the line relay of the connector is opened at the bridge cut-off springs with the result that the line relay again deenergizes, causing the deenergization of the release relay. This same cycle of operation is repeated as long as the back bridge relay is held in energized position. According to another feature of the invention, the fluttering 30 of the calling line switch, as above set forth, is prevented by providing the back bridge relay with a pair of springs for grounding the release trunk, thereby holding the lineswitch operated until the back bridge relay or connector switch is released.

These and other features of the invention not specifically mentioned at this time will be better appreciated when the following description is taken in conjunction with the accompanying drawings.

Referring now to the drawings comprising Figs. 1 and 2, there is shown, by means of the usual circuit diagrams, a sufficient amount of the apparatus embodying the principles of the invention to enable the invention to be described and understood.

Referring to Fig. 1, the substation A is one of a plurality of ordinary automatic substations terminating in the local automatic exchange, and is provided with the usual talking equipment and ringer, and also with a calling device of well-known type which is indicated by the reference character S, through the medium of which the subscriber controls the local exchange switches.

The line conductors 11 and 12 extend to the exchange, where they terminate in the multiplied connector bank contacts 13 and 14 and in the lineswitch PLS, which may briefly be described as the well-known plunger

type or Keith lineswitch having a plunger which controls the connection of the subscriber's line to an idle trunk line. The plungers of all the lineswitches are controlled by a common master switch (not shown) in such a manner that the plungers of all the idle lineswitches of the group are always standing opposite an idle trunk. A plurality of these lineswitches are given access to a group of trunk lines extending to connector switches. One of the trunk lines to which the lineswitch PLS has access is shown in the drawing as extending to the improved connector switch CONN, which is mechanically the same construction as the well-known Strowger type of switch. The connector switch has access to subscribers' lines, such as A', from certain levels and to a plurality of groups of trunk lines from a special level or levels. Shaft-controlled springs, such as 85 spring 84, which operate when the switch shaft and wipers are raised opposite a trunk hunting level, are provided in order to permit a switching through relay to switch the talking conductors straight through to the 90 trunk line in the same manner as in the well-known Strowger selector switch. Similar shaft springs, such as 85, are also operated on the special levels in order to prevent the restricted subscribers from completing connections with the trunk lines therein. Just below the connector is shown the well-known busy, dial tone, and ringing machines which are common to the connectors.

The substation A' is similar to the substation A and is accessible to the connectors over bank contacts 94, 95, and 97. The line of substation A' terminates in a lineswitch (not shown), which is similar to the lineswitch PLS.

The connectors, such as the connector CONN, are also accessible to toll operators by way of lineswitches, the bank contacts of which are connected in multiple with the bank contacts of the lineswitches individual to the 110 subscribers' lines.

Meters, such as meter 100, are provided for each subscriber's line in order to register the number of completed local connections. The meters can be connected to either negative 115 battery or ground by way of terminals such as terminals 101, 102, and 103, depending upon whether or not the subscriber is entitled to unrestricted or restricted service. With the meter connected by the jumper extending between terminals 101 and 102, the subscriber A is entitled to unrestricted service, while if the meter were connected to terminal 103 instead of terminal 102, the subscriber A would be restricted to local 120 connections only.

In Fig. 2, only the two test contacts of each of the trunk lines in the "O" level, or the special trunk hunting level, have been shown. In the particular case illustrated, this level 130

is divided into three groups of trunks, the first group consisting of the first four pairs of contacts, the second group consisting of the next four pairs of contacts, and the last group consisting of the last two pairs of contacts. The first group of trunks extend to the toll recording operator's position, while the last two groups extend to nearby exchanges. It will be noted that all but the last pair of test contacts in a group are connected by a jumper, such as jumper 106, while the last pair of test contacts of the group are not connected. This is done in order to permit the connector to rotate from all busy trunk lines in the group except the last, where if the last trunk is busy the connector stops and transmits the busy signal to the calling subscriber. The individual subscriber's test contacts, such as 95 and 96 (Fig. 1), are not connected; therefore, there will be no automatic rotation therefrom in case such line is called and found busy.

With this general description of the drawings in mind, the operation of the circuits will now be described in detail. For this purpose, it will now be assumed that subscriber A desired to complete a local connection to the line of subscriber A'.

Responsive to the removal of the receiver by the calling subscriber A, a circuit is closed for energizing line relay 15 of the lineswitch PLS as follows: ground by way of the master switch supervisory ground lead, the B. C. O. springs 18, subscriber's line conductor 12, through the calling subscriber's loop, subscriber's line conductor 11, the B. C. O. springs 17, and through the winding of line relay 15 to battery. Line relay 15 energizes over the above-traced circuit and at armature 16 closes a circuit from ground over the master switch supervisory ground lead for operating the pull down winding 19 of the lineswitch PLS. The pull down winding 19 energizes and causes the operation of the plunger arm. The operation of the plunger arm forces the bank contacts 21 to 24, inclusive, into engagement with their associated bank contacts 21' to 24', inclusive, it being assumed that the plungers of the idle lineswitches of the group containing the lineswitch PLS have been standing opposite this set of bank contacts. In addition to the operation of the plunger arm, the B. C. O. armature operates and opens the B. C. O. springs 17 and 18, thereupon opening the circuit for the line relay 15. As soon as the plunger arm closes the line contacts 21 and 21' and 24 and 24', a circuit for energizing the line relay 26 of the connector CONN may be traced as follows: from ground by way of the lower winding of line relay 26, normally closed springs controlled by armature 38, resting contact of armature 70 and said armature, contact 24', contact 24, line conductor 12, over the calling subscriber's loop, line conductor 11, contact

21, contact 21', armature 66 and its resting contact, normally closed springs controlled by armature 37, and through the upper winding of line relay 26 to battery. Line relay 26, upon energizing, closes a circuit for energizing release relay 27 in series with relay 28. Due to the high resistance of relay 27, relay 28 is not energized over this circuit. Release relay 27 at armature 41 connects ground to release trunk conductor 88 in order to establish a holding circuit by way of contacts 23 and 23' for the BCO winding 20 of the lineswitch before line relay 15 has had time to deenergize. At contact 40, release relay 27 prepares a circuit for the discriminating relay 35 which will now energize in case the calling subscriber's meter is connected to ground through terminal 103. At armature 41, release relay 27 closes a circuit for energizing the combined change-over and ring cut-off relay 32 as follows: from grounded release trunk conductor 88, normally closed off-normal springs 82 and through the lower winding of relay 32 to battery. At armature 42 release relay 27 prepares the impulsing circuit for the operating magnets of the switch, at armature 43 and its resting contact it opens the circuit of the release magnet RLSE and at armature 43 and its working contact it prepares a circuit for relays 28 and 29. The combined change-over and ring cut-off relay 32, upon energizing, at armature 62 prepares a locking circuit for itself and at armature 63 prepares the circuit for the vertical magnet VERT. The operation of armatures 60, 61, and 64 at this time are without effect. At armature 65, change-over relay 32 connects the dial tone machine to the lower talking conductor of the connector as follows: from armature 65, resting contact of armature 55 and said armature, resting contact of armature 78 and said armature, the small capacity condenser C, the lower talking condenser, resting contact of armature 70 and said armature, to the lower talking conductor of the connector from where the tone is transmitted to the calling subscriber in the well-known manner. It should possibly be mentioned here that the combined change-over and ring cut-off relay 32 is made slightly slow to pull up in order to permit the discriminating relay to pull up and lock in case a restricted subscriber is calling.

Upon receipt of the well-known dial tone, the calling subscriber at substation A will operate his calling device S in accordance with the tens digit of the called subscriber's number. Line relay 26 is deenergized once for each impulse transmitted by the calling device S. Line relay 26, upon deenergizing, responsive to the first impulse, closes a circuit for energizing relay 28 as follows: from ground by way of armature 69, armature 43 and its working contact, armature 54 and its resting contact, normally closed springs con-

trolled by armature 39 and through the winding of relay 28 to battery. A branch of this circuit continues by way of armature 59, resting contact of armature 53 and said armature, 5 interrupter contacts of the rotary magnet, and through the winding of relay 29 to battery. It should also be mentioned at this time that the normally closed springs controlled by armature 39 close a direct short 10 around the release relay 27 to render this relay slow to release. Relays 28 and 29 energize over the above-traced circuit and relay 28 at armature 44 closes a circuit for energizing relay 31; at armatures 45 and 47 15 completes a new and more direct circuit for the relays 28 and 29. This circuit may be traced from ground at armature spring 69 by way of armature 43 and its working contact, armature 47 and its working contact, 20 normally closed springs controlled by armature 39, to the relay 28 and by way of armature 45 to relay 29. Relay 29, upon energizing, at armature 49 completes a circuit for energizing the vertical magnet VERT as follows: ground by way of armature 42, armature 49, armature 63 and its working contact, to the vertical magnet and battery. By 25 the operation of the vertical magnet the switch shaft is raised one step, thereby opening the off-normal springs 82. Relay 32, however, is maintained in operated position over a circuit extending from ground at the working contact of armature 57 and the locking contact of armature 62 of relay 32.

30 After the termination of the first impulse, line relay 26 is again energized, thereby re-establishing the circuit for relay 27. It should possibly be mentioned at this time that the current flow over the circuit through the high resistance winding of relay 27 to relay 28 and 29 is insufficient to maintain relays 28 and 29 in operated position. Relay 28, however, is so adjusted that it will slowly fall back only after a long energization of relay 40 45. Relay 28, therefore, maintains its armatures attracted for the duration of a series of impulses, while the relay 29 is so adjusted that it attracts and retracts its armatures for each impulse. When relay 26 pulls up at the end of the first impulse relay 29 releases 50 and opens the circuit of the vertical magnet. Each succeeding impulse of the series operates relay 29 and the vertical magnet to cause the switch shaft to raise the wipers 90 to 93, 55 inclusive, opposite the group in which the called line terminates. Shortly after the last vertical impulse, relay 28, which has been maintained energized throughout the vertical impulses, releases and at armature 44 opens the circuit of relay 31 whereupon the latter 60 relay deenergizes. Relay 31, upon deenergizing, at armature 57 opens the locking circuit of relay 32, whereupon the latter relay deenergizes and switches the impulsing circuit at armature 63 from the vertical magnet

to the rotary magnet ROT. At armature 62 relay 32 opens another point in its locking circuit and at armature 65 disconnects the dial tone from the lower talking conductor. The connector switch is now ready to receive the next series of impulses for rotating the switch wipers into engagement with the bank contacts of the desired line.

Responsive to the next series of impulses transmitted by the calling subscriber A, line 75 relay 26 again causes the operation of relays 28, 29, and 31 in the same manner as previously described. Each time the impulse repeating relay 29 energizes, a circuit may be traced for operating the rotary magnet as follows: ground by way of armature 42, armature 49, armature 63 and its resting contact, armature 75 and winding of rotary magnet ROT to battery. By the operation of the rotary magnet the switch wipers 90 to 93, 85 inclusive, are directly operated into engagement with the bank contacts 94 to 97, inclusive. The operation of the connector now depends upon whether the called line is busy or not.

90 It will now be assumed that the line of substation A' is busy when called. Under these circumstances, there will be a ground potential upon the test contact 95 and when the test wiper 91 comes to rest in engagement 95 with contact 95, busy relay 30 will be energized. It will be remembered that relay 28, being slow to release, has maintained relay 31 in operated position so that a circuit for energizing busy relay 30 may be traced as follows: from ground on test contact 95, wiper 91, resting contact of armature 80 and said armature, normally closed springs controlled by armature 73, armature 67 and its resting contact, armature 56 and its working contact, and through the winding of busy relay 30 to battery. Shortly after the termination of impulses, the slow acting relay 28 deenergizes and opens the circuit of relay 31. Relay 31 is rendered slow to release because 105 said relay is short-circuited by the operation of armature 51 of relay 30. Relay 30, upon energizing, at armature 52 opens a point in the circuit of switching relay 34, at armature 53 prepares a circuit to wiper 92 which, however, is without effect at this time, and at armature 54 and its working contact prepares a locking circuit for itself and at its resting contact opens the initial energizing circuit for relay 28. Shortly after relay 28 110 deenergizes, relay 31 deenergizes and at armature 56 and its resting contact closes a point in the circuit for the switching relay 34 which heretofore has been held open. At the normally closed springs controlled by armature 115 56, relay 31 closes a locking circuit for maintaining busy relay 30 in energized position, at armature 58 opens the circuit extending to the wiper 92, and closes the contacts 59 which, however, at this time are without effect. The 120

circuit for maintaining busy relay 30 in energized position may be traced as follows: ground by way of armature 69, armature 43 and its working contact, armature 54 and its working contact, armature 76, normally closed 5 springs controlled by armature 56, and through the winding of the busy relay 30 to battery. At armature 55 and its working contact busy relay 30 connects the well-known 10 busy tone by way of armature 78 and the small capacity condenser C to the lower talking conductor. The calling subscriber A is now given the busy tone in the well-known manner.

When the calling subscriber hears the well-known busy tone, he will replace his receiver, thereby opening the circuit of the line relay 26. At armature 39 line relay 26 opens the circuit of release relay 27 which thereupon deenergizes and at armature 41 removes ground from the release trunk conductor 88, thereby permitting the release of the calling lineswitch. At armature 42 release relay 27 opens the impulsing circuit to the vertical 25 and rotary magnets and at armature 43 and its working contact opens the locking circuit of busy relay 30, whereupon said busy relay releases. At armature 43 and its resting contact release relay 27 closes the circuit for operating the release magnet RLSE as follows: ground by way of armature 69, armature 43 and its resting contact, off-normal springs 83, and through the winding of the release magnet RLSE to battery. The release magnet 30 energizes over the above-traced circuit and restores the switch wipers to the normal position, after which the off-normal springs 83 open the circuit of release magnet in the usual manner. All the apparatus used to extend 35 the connection has now been returned to its normal position and may be used for other calls.

Having explained what occurs when a called line is busy, it will now be assumed that the called line is idle. Such being the case, when the test wiper 91 comes to rest in engagement with the test contact 95, it will find no ground potential and the busy relay 30 will not be energized. Instead, when the 40 slow acting relay 28 falls back, the circuit of relay 31 will be opened, whereupon said relay will quickly fall back because the busy relay has not been operated to short-circuit relay 31 at armature 51. As soon as relay 31 falls back, a circuit may be traced for energizing 45 switching relay 34 as follows: from ground by way of armature 42, armature 52, shaft control spring 84 and its resting contact, upper winding of switching relay 34, resting 50 contact of armature 56 and said armature, resting contact of armature 67 and said armature, normally closed springs controlled by armature 73, armature 80 and its resting contact, test wiper 91, bank contact 95, and winding 55 of the BCO winding of the called line-

switch (not shown) to battery. Upon the closure of the above-traced circuit, the BCO winding of the called lineswitch operates to clear the line of station A' from its normal battery and ground connections. Switching 60 relay 34 also energizes over the above-traced circuit in series with the BCO winding of the called lineswitch and at armature 74 completes a locking circuit for itself. At armature 72 switching relay 34 prepares the circuit for operating the calling subscriber's meter; at armature 73 connects ground to the test wiper 91 in order to hold the called lineswitch; at armature 74 and its two working contacts closes a locking circuit for the lower winding of relay 34 and by the upper contact prepares a locking circuit for the ring cut-off relay 32; at armature 75 opens the rotary magnet circuit; at armature 76 opens a point in the locking circuit of the busy relay 30; at armature 78 prepares the circuit for transmitting the well-known ring-back tone to the calling subscriber by way of the small capacity condenser C; and at armatures 71 and 77 connects the ringing current to the line conductors of the connector for ringing the called subscriber A'. The ringing current may be traced as follows: Interrupted generator by way of armature 87, resting contact of armature 64 and said armature, armature 77, wiper 93, line contact 97, through the bridged ringer and condenser at substation A', line contact 94, wiper 90, armature 71, armature 60 and its resting contact, and through the upper winding of ring cut-off relay 32 to battery. The ring-back tone extends from armature 77 by way of armature 78 and the small capacity condenser C to the lower talking conductor from whence it is transmitted to the calling subscriber in the usual manner.

When the called subscriber answers, the ring cut-off relay 32 energizes and at armature 62 completes a locking circuit for itself. At armatures 60 and 64 relay 32 disconnects the ringing current from the called line and completes the talking circuit between the calling and the called subscribers. In addition, relay 32 at armature 61 completes a circuit for energizing the calling subscriber's meter magnet 100 over the following circuit: ground by way of armature 79, armature 72, working contact of armature 61 and said armature, armature 40, contacts 22' and 22, through the winding of meter magnet 100, terminal 101, jumper, and terminal 102 to battery. The calling subscriber's meter is operated over this circuit to register the call. Responsive to the operation of the ring cut-off relay a circuit is closed for energizing the back bridge relay 25 as follows: ground by way of lower winding of back bridge relay 25, working contact of armature 64 and said armature; armature 77, wiper 93, bank contact 97, the subscriber's loop, bank contact 94, wiper 90, armature 71, armature 60 and its

working contact, and through the upper winding of back bridge relay 25 to battery. Back bridge relay 25, upon energizing, at armature 36 grounds the release trunk conductor 88 in order to maintain the calling lineswitch in operated position. At armature 37 and 38 back bridge relay 25 reverses the current flow over the calling subscriber's loop.

In practice, it has been found necessary to have the back bridge relay ground the release trunk in order to prevent the fluttering of the calling lineswitch. This difficulty, however, is not encountered when there are intervening switches between the calling lineswitch and the connector switch. Heretofore, the fluttering of the calling lineswitch was apt to occur when the calling subscriber hung up before the called subscriber. After conversation, assuming that the calling subscriber is the first to replace his receiver, the connector line relay releases and at armature 39 opens the circuit of the slow to release relay 27. Assuming that the back bridge relay at armature 36 does not ground the release trunk conductor 88, the release relay 27 upon deenergizing will, in the assumed case, remove ground from release trunk conductor 88 thereby opening the energizing circuit of the BCO winding 20 of the calling lineswitch. When the circuit to the BCO winding is opened the BCO armature will release and permit the closure of springs 17 and 18 whereupon a circuit may be traced for energizing line relays 15 and 26 as follows: ground by way of lower winding of line relay 26, armature 37 and its working contact, resting contact of armature 66 and said armature, contacts 21' and 21, contacts 17 and to the winding of line relay 15 to battery. Line relay 15 and line relay 26 will energize in series over the above-traced circuit. At armature 39 line relay 26 again completes the circuit for slow to release relay 27 before release relay 27 has had time enough to permit the release of the ring cut-off and switching relays and before the closure of the release magnet circuit through armature 43 is effective. In this manner the release relay 27 is again energized and again grounds the release trunk conductor 88 to again cause the operation of the BCO armature springs. Due to the operation of the BCO armature the circuits of the line relays are opened with the result that the circuit of the slow to release relay 27 is again opened. This intermittent operation of the line relays and the slow to release relay 27 continues until the called subscriber hangs up or until the circuit of the back bridge relay 25 is opened. Since, however, in the present case the back bridge relay 25 at armature 36 grounds the release trunk conductor 88, it is impossible for the BCO armature to release and close the circuits to the line relays of the lineswitch and

connector. In the present case we will assume that the calling subscriber is the first man to replace his receiver. Under these circumstances the line and release relays deenergize while the back bridge relay 25 is maintained energized by the called subscriber. When the release relay deenergizes it closes at armature 43 the circuit for operating the release magnet whereupon said magnet operates and releases the switch. Due to the release of the switch the circuit of the back bridge relay is opened by the release of the ring cut-off and switching relays or when the wipers 90 and 93 are removed from the bank contacts of the called line in case the ring cut-off and switching relays are slow in releasing. Back bridge relay 25, upon releasing, removes ground from the release trunk conductor 88 thereby permitting the calling lineswitch to return to normal position. In case the called subscriber is the first to replace his receiver the back bridge relay releases and straightens out the current flow so that there is no danger of causing the lineswitch to flutter when the calling subscriber replaces his receiver.

Having described the detailed operation of the connector CONN in establishing a connection between subscriber A and subscriber A', a detailed description will now be given of the operation when the subscriber A desires to complete a connection with an idle trunk line in one of the groups in the restricted level. The operation of the connector is the same regardless of whether the subscriber is calling the toll recording operator or either one of the branch exchanges by way of the restricted level shown in Fig. 2. Responsive to the removal of the receiver at substation A, the lineswitch PLS operates in the same manner as previously described to seize an idle connector switch. It will be assumed that the connector CONN shown in Fig. 1 is the connector seized by the lineswitch PLS. The operation of the connector is identical with the operation previously described with the exception, however, that when the switch shaft wipers are raised opposite the restricted level shown in Fig. 2 the shaft control springs 84 and 85 are operated. Shaft spring 84, when operated, opens the circuit of the regular switching relay 34 at its resting contact and at its working contact prepares the circuit for the switching through relay 33. Switching through relay 33, however, does not energize at this time because it is necessary for wiper 91 to find negative battery potential. Since the calling subscriber is an unrestricted subscriber and therefore entitled to extend calls over the restricted level, the operation of the shaft control spring 85 at this time is without effect because the discriminating relay 35 has not been operated. Since the operation of the connector is the same regardless of whether the toll recording operator or either one of

the branch exchanges is being called, we will assume in this case that the subscriber A desires to complete a connection with the toll recording operator. In this case, the calling subscriber A will send the digit 1 in order to cause the wipers to rotate one step into engagement with the bank contacts of the first trunk extending to the toll recording operator's position. The manner in which the connector is rotated onto the first contact of the group is the same as previously described. If the first trunk line is idle the connector will stop and complete the connection to the toll recording operator in the same manner as described for the connection to the called subscriber A'. The operation of the connector, however, is different in case the first trunk line is busy. Assuming that the first trunk line is busy, a circuit may then be traced for the busy relay 30 as follows: from ground by way of test contact 104, test wiper 91, resting contact of armature 80 and said armature, normally closed springs controlled by armature 73, armature 67 and its resting contact, armature 56 and its working contact, and through the winding of busy relay 30 to battery. It will be remembered that relay 28 is slow to release after the end of the rotary impulses and therefore relay 31 is held by relay 28 until relay 28 releases. Before relay 28 releases, however, the busy relay 30 is energized over the above traced circuit and at armature 51 prepares the short circuit for relay 31 so as to render relay 31 slow to release as soon as the normally closed springs controlled by armature 44 have closed. As soon as relay 28 releases a circuit for energizing relay 29 may be traced as follows: ground by way of test contact 104, jumper 106, lower test contact engaged by wiper 92 and said wiper, armature 58, armature 46, working contact of armature 53 and said armature, interrupter springs of the rotary magnet, and winding of relay 29 to battery. Relay 29, upon energizing, at armature 48 opens the short circuit around the relay 31 and at the same time substitutes a circuit for maintaining relay 31 in energized position. This circuit extends from grounded armature 48 by way of its working contact and through the normally closed springs controlled by armature 44. At armature 50 relay 29 closes a locking circuit for itself as follows: ground by way of armature 69, armature 43 and its working contact, armature 47 and its resting contact, armature 50, interrupter springs of the rotary magnet, and winding of relay 29 to battery. Relay 29 at armature 49 closes a circuit for energizing the rotary magnet. The operation of the rotary magnet causes the switch wipers to be stepped into engagement with the next set of bank contacts associated with the next trunk line. The rotary magnet, near the end of its stroke, opens its interrupter contacts, thereby interrupting the circuit of relay 29 which, thereupon, deenergizes and in turn opens the circuit of the rotary magnet. Relay 29, upon deenergizing, again establishes the short circuit for relay 31 in case the test relay 30 is operated and at armature 50 opens its own locking circuit. Assuming that all but the last trunk line extending to the toll recording operator's position is busy, the connector will be rotated to this last set of contacts in the same manner as just described. Assuming that the last trunk line is idle no circuits will be completed for the busy relay or relay 29. Since relay 30 is not energized relay 31 is not short-circuited, therefore the latter relay immediately deenergizes and closes the circuit for operating the switching-through relay 33 as follows: from ground by way of armature 42, armature 52, shaft control spring 84 and its working contact, upper winding of switching through relay 33, resting contact of armature 56 and said armature, resting contact of armature 67 and said armature, normally closed springs controlled by armature 73, armature 80 and its resting contact, wiper 91, and test contact 107 to negative battery. Switching through relay 33, upon energizing, at armatures 66 and 70 disconnects the line relay 26 and connects the talking conductors of the connector straight through to the wipers 90 and 93. At armature 68 relay 33 establishes a locking circuit for itself before its energizing circuit is opened at armature 67; and at armature 69 opens a point in the circuit of the release magnet in order to prevent the release of the switch when the line and release relays 26 and 27 deenergize. Before release relay 27 deenergizes, however, ground is sent back over the seized trunk line in the well-known manner in order to hold the switching through relay in operated position. This circuit extends from ground which is now connected to test contact 107, wiper 91, resting contacts of armature 80 and said armature, normally closed springs controlled by armature 73, armature 67 and its working contact, armature 68, and through the lower winding of switching through relay 33 to battery. The remainder of a connection to the toll recording operator's position may be set up in any well-known manner. The release of line relay 26 and release relay 27 at this time are without effect since the circuit of the release magnet is open. The ground which holds up the switching through relay 33 also extends over the trunk conductor 88 and maintains the calling lineswitch PLS in operated position. After conversation, ground is removed from contact 107 in the well-known manner, thereby removing the holding ground from the release trunk conductor 88 and from the holding winding of switching through relay 33. Responsive to this removal of ground the lineswitch PLS returns to normal position.

tion in the usual manner and the switching through relay 33 deenergizes and at armature 69 completes the circuit for the release magnet RLSE whereupon the connector is released in the same manner as previously described.

In order to describe the restricted service features, it will now be assumed that the meter magnet 100 associated with the line of the substation A is connected by jumpers to terminal 103 instead of 102. The meter magnet 100, therefore, will be connected to ground instead of battery. It will now be assumed that the restricted subscriber A desires to complete a connection to subscriber A'. The operation of the lineswitch PLS and the connector CONN is identical with the operation previously described except that the discriminating relay 35 is energized as soon as the release relay 27 pulls up. The circuit for energizing the discriminating relay 35 may be traced as follows: from ground by way of terminal 103, jumper, terminal 101, meter magnet 100, contacts 22 and 22', armature 40, armature 61 and its resting contact, normally closed springs controlled by armature 81, and through the high resistance winding of relay 35 to battery. Due to the high resistance winding of relay 35 the meter magnet 100 is not operated. Since ring cut-off relay 32 is slightly slow to pull up, the circuit of relay 35 will not be opened at armature 61 until relay 35 has had time to pull up. Relay 35, upon energizing over the above-traced circuit, at armature 81 closes a locking circuit for itself by way of grounded release trunk conductor 88 and at armature 79 prepares the circuit for operating the calling subscriber's meter. At armature 80 discriminating relay 35 closes a new circuit by way of shaft springs 85 for test wiper 91. Since a restricted level in this case has not been called the shaft control springs 85 are not operated. The testing circuit now extends by way of armature 80 and its working contact, shaft control spring 85 and its resting contact to the test wiper 91. The operation of the connector is the same as previously described with the exception that when the called subscriber answers a circuit is completed for operating the calling subscriber's meter as follows: from ground by way of terminal 103, jumper, terminal 101, meter magnet 100, contacts 22 and 22', armature 40, armature 61 and its working contact, armature 72, armature 79 and its working contact and through the low resistance to battery. The meter magnet 100 is held energized over this circuit until the connector is released which it does in the same manner as previously described.

It will now be assumed that the restricted subscriber A attempts to complete a call with one of the trunk lines in the restricted level. In this case the operation of the connector is

the same as previously described and when the switch shaft and wipers are raised opposite the restricted level the shaft control springs 84 and 85 are operated. As soon as shaft control spring 85 is operated a circuit may be traced for energizing the busy relay 30 as follows: ground by way of working contact of spring 85 and said spring, working contact of armature 80 and said armature, and over the previously traced circuit to the winding of relay 30 and battery. Relay 30 energizes and at armature 52 opens the circuit of the switching through relay 33. In case the calling subscriber should attempt to dial another digit the line relay would operate in the same manner as previously described but no impulses would be sent to relays 28 or 29 because at armatures 54 and 53 the busy relay 30 has opened the initial energizing circuit for relays 28 and 29. The switch, therefore, remains standing opposite the restricted level. When the relay 31 deenergizes, which it does shortly after the termination of the vertical impulses, a locking circuit is closed for the busy relay from ground by way of armature 69, armature 43 and its working contact, armature 54 and its working contact, armature 76, normally closed springs controlled by armature 56 and through the winding of the busy relay 30 to battery. At armature 55 the busy relay transmits the busy tone to the calling subscriber in the same manner as previously described. It will be noted that by the combined operation of the discriminating relay 35 and shaft springs 85 the circuit to test wiper 91 is opened so that in case the subscriber should rotate the switch wipers the said circuit to the test wiper is open.

When the calling subscriber hears the well-known busy tone he will replace his receiver and the lineswitch PLS and connector CONN will release in the same manner as previously described.

Although only one level has been shown as a restricted level the shaft springs 84 and 85 could also be made to operate on other restricted levels in case the same were provided.

Incoming calls from the toll recording operator's position and calls from the nearby branch exchanges can be made over trunk lines extending to the local exchange and terminating therein in lineswitches similar to the lineswitch PLS. These lineswitches have their bank contacts connected in multiple with the bank contacts such as the lineswitches illustrated by the lineswitch PLS. The connectors such as the connector CONN, therefore, are accessible from these trunk lines by way of the lineswitches. Assuming that the connector switch CONN has been seized by one of the lineswitches associated with one of the incoming trunks the connector will be operated in the usual manner to complete the connection to the desired subscriber and when the called subscriber answers the back bridge

relay 25 will energize and reverse the flow of current in the talking conductors of the trunk line in order to provide supervision to the calling operator. The release of the connections takes place in the well-known manner.

Having described the invention, its utility and operation, what is considered new and is desired to have protected by Letters Patent will be set forth in the appended claims.

What is claimed is:

1. In a telephone system, a release relay for controlling the release of an established connection, an impulse repeating relay for repeating impulses to cause the establishment of a desired connection, means for short-circuiting said release relay in order to send impulses to said repeating relay, and a change-over relay connected in parallel with said repeating relay to assist in the establishment of the desired connection.

2. In a telephone system, a release relay for controlling the release of an established connection, an impulse repeating relay for repeating impulses to cause the establishment of a desired connection, means for short-circuiting said release relay in order to send impulses to said repeating relay, a change-over relay connected in parallel with said repeating relay and connected in the circuit of said release relay, and means controlled by said change-over relay for assisting said repeating relay in establishing the desired connection.

3. In an automatic switch having directive and hunting movements, an impulse repeating relay having only a single winding, means for controlling said repeating relay over its winding to send impulses to the operating magnets to directively operate said switch, and means for energizing and de-energizing said repeating relay over its winding thereby sending impulses to cause the operation of said switch in its hunting movement.

4. In an automatic switch having a directive movement and a hunting movement, an impulse repeating relay for sending impulses to the operating magnets, a change-over relay connected in parallel with said repeating relay for controlling the change-over from the directive to the hunting movement, means for controlling said change-over and said repeating relays to directively operate said switch, and means for energizing and deenergizing said repeating relay to send impulses to cause the operation of said switch in its hunting movement.

5. In an automatic switch having a directive movement and a hunting movement, an impulse repeating relay for sending impulses to the operating magnets, a release relay connected in series with said repeating relay for controlling the release of said switch, means for controlling said release and repeating re-

lays to directively operate said switch, and means for energizing and deenergizing said repeating relay to send impulses to cause the operation of said switch in its hunting movement.

6. In an automatic two-motion connector switch for use in telephone systems, a release relay for controlling the release of said switch, an impulse repeating relay for sending impulses to the operating magnets of said switch to cause said switch to be operated in its two motions, means for short-circuiting said release relay in order to send impulses to said repeating relay, and a change-over control relay for controlling the change-over from one motion of the switch to the other connected in the circuit of said release relay and controlled independent of said repeating relay.

7. In a telephone system, a group of trunk lines, a connector switch having directive and automatic hunting movements, means for operating said switch in its directive and automatic movements to select an idle one of said trunk lines, testing and stepping circuits for controlling the automatic movement of said switch, a relay for controlling said testing and stepping circuits, means for rendering said relay slow acting as long as the switch encounters busy trunk lines, said means ineffective when the switch encounters an idle trunk line thereby permitting said relay to fall back quickly, and means responsive to the falling back of said relay for causing said switch to seize said trunk line.

8. In a telephone system, a group of trunk lines, a connector switch having directive and automatic movements, means for operating said switch in its directive and automatic movements to select an idle one of said trunk lines, a test relay and a stepping relay in said switch for controlling the automatic movement of said switch, a circuit for said test relay, a circuit for said stepping relay, a third relay for controlling the circuits of said test and stepping relays, contacts on said stepping relay for closing an energizing circuit for said third relay, and contacts on said test relay for short-circuiting said third relay to render said third relay slow to release during the automatic movement of said switch.

9. In a telephone system, subscribers' lines, a connector switch having access to said lines, a release trunk conductor in said switch, means controlled by a calling subscriber for seizing said switch and for operating said switch to complete a connection to one of said lines, means in said connector responsive to its seizure for grounding said conductor, a relay in said connector, means responsive to the called subscriber answering for operating said relay to reverse the direction of current flow to the calling line, and contacts on said relay for connecting an additional ground to said conductor.

10. In a telephone system, a plunger line-switch, a calling subscriber's line terminating in said lineswitch, a connector switch accessible to said lineswitch, a called subscriber's line accessible to said connector, means for operating said lineswitch to seize said connector responsive to the initiation of a call by the calling subscriber, a release trunk conductor in said connector extending to said lineswitch, means in said connector responsive to said seizure for grounding said conductor to hold said lineswitch operated, means controlled by the calling subscriber for operating said connector to complete a connection with said called subscriber's line, a relay in said switch, means responsive to the called subscriber answering for operating said relay to reverse the direction of current flow to the calling line-switch, means responsive to the calling subscriber replacing his receiver for removing said ground connection from said release trunk conductor and for releasing said switch and contacts on said relay for grounding said conductor to prevent said lineswitch from fluttering due to said reversal.

11. In a telephone system, a calling subscriber's substation set, a connector switch, means including tone circuits in said connector for transmitting a dial tone, a busy tone, and a ring-back tone to the calling subscriber, and means comprising a small capacity condenser included in said tone circuits for reducing the tone heard by the calling subscriber in order to prevent disagreeable noises in the receiver of the calling subscriber's substation set.

12. In a telephone system wherein a connector switch transmits a dial tone, a busy tone, and a ring-back tone to the calling subscriber through the same small capacity condenser, a combined change-over and ring cut-off relay for controlling the transmission of the dial tone, a busy relay for controlling the transmission of the busy tone, a switching relay for controlling the transmission of the ring-back tone, said combined relay controlling the disconnection of said ringback tone, and means for operating said relays for the purposes set forth.

13. In a telephone system, subscribers' lines, a connector switch accessible from said lines and having access to said lines, trunk lines also accessible to said connector, a measured service device for each subscriber's line, some of said subscribers' lines having their devices connected in such a manner as to restrict such subscribers from operating said connector to complete connections to said trunk lines, and means including only a single conductor for operating said devices and for preventing the restricted subscribers from operating said connector to complete connections with said trunk lines.

14. In a telephone system, a subscriber's

line, other subscribers' lines, groups of trunk lines, a connector switch having access to said subscribers' lines and said trunk lines, a measured service device, means including a circuit in said connector for operating said device responsive to the connector completing a connection from said subscriber's line to an idle one of said other lines, and means including a circuit in said connector for preventing said subscriber from completing a connection with any one of said trunk lines, said circuits including a common conductor extending from said device to said connector switch.

15. In a telephone system, subscribers' lines, a connector switch accessible to said lines and having access to said lines, trunk lines accessible to said connector switch, a measured service device for each subscriber's line, terminal connections for connecting said devices to either battery or ground, the subscribers' lines having their devices connected to ground being restricted to connections to said subscribers' lines while the subscribers' lines having their devices connected to battery are unrestricted and are entitled to establish connections to both the subscribers' lines and said trunk lines, a discriminating relay in said connector, means for operating said relay over a circuit including a restricted subscriber's device responsive to the seizure of said switch by a restricted subscriber, said relay non-operative when a non-restricted subscriber seizes said switch, means controlled by said relay when in operated position for preventing said connector from completing a connection with any trunk line but not preventing said connector from completing a connection with any subscriber's line if idle, and normally closed and normally open contacts on said relay for operating said devices over a circuit including a portion of said first circuit when the called subscriber answers, said normally closed contacts for operating the non-restricted subscribers' devices and said normally open contacts for operating the restricted subscribers' devices dependent upon the operated condition of said relay.

16. In a connector switch, a release relay for controlling the release of said switch, an impulse repeating relay for repeating impulses to the magnets of said switch to control said switch in the establishment of a desired connection, and a line relay controlled by a calling line for short circuiting said release relay in order to send impulses to said repeating relay.

17. In a connector switch, a release relay for controlling the release of said switch, an impulse repeating relay for repeating impulses to operate said switch, and means for short circuiting said release relay to send impulses to said repeating relay.

18. In a connector switch, an impulse repeating relay for repeating impulses to oper-

ate said switch, a change-over relay connected in parallel with said repeating relay, and means controlled by said change-over relay for assisting said repeating relay in operating said switch.

5 19. In a telephone system, subscribers' lines, a connector switch having access to said lines, means controlled by a calling line for seizing said connector and operating it to 10 complete a connection to one of said lines, a release trunk conductor in said connector grounded when said connector is seized, and means responsive to the answering of the 15 called subscriber for placing an additional ground on said conductor.

20 20. In an automatic hunting switch, a relay, means for sending impulses to said relay during the hunting movement of said switch, and means for making said relay slow acting 20 as long as said switch continues its hunting movement and for making said relay quick acting as soon as the hunting movement ceases.

25 21. In an automatic hunting switch having access to a group of trunk lines, a relay, means for sending impulses to said relay during the hunting movement of said switch, and means for making said relay slow-acting as long as 30 said switch encounters busy trunk lines and for making said relay quick acting as soon as an idle trunk line is found.

35 22. In an automatic hunting switch, a testing circuit, a relay for closing said circuit during the hunting movement of said switch, and means for making said relay slow acting 35 as long as said switch continues its hunting movement and for making said relay quick acting as soon as the hunting movement ceases.

40 40. In witness whereof, I hereunto subscribe my name this 16th day of April, A. D. 1928.
NORMAN H. SAUNDERS.
